UNITED STATES PATENT OFFICE.

FREDERIC S. SEAGRAVE, OF COLUMBUS, OHIO.

BASE ATTACHMENT FOR LADDERS.

SPECIFICATION forming part of Letters Patent No. 625,066, dated May 16, 1899.

Application filed March 9, 1899. Serial No. 708,301. (No model.)

To all whom it may concern:

Be it known that I, FREDERIC S. SEAGRAVE, a citizen of the United States, residing at Columbus, in the county of Franklin and State 5 of Ohio, have invented a certain new and useful Improvement in Base Attachments for Ladders, of which the following is a specification.

My invention relates to the improvement 10 of adjustable ladder-bases; and the objects of my invention are to provide a ladder or the lower section thereof with an improved supporting-base which will provide a substantial support for the ladder and obviate any tendency 15 toward the same slipping when in a raised position and which at the same time will present an extended bearing-surface for the ladder-section which will support the ladder against leaning or tipping laterally, to so 20 construct my improved ladder-base as to admit of the adjustment of the sections thereof to desirable angles, and to produce other improvements in details of construction and arrangement of parts which will be more fully 25 pointed out hereinafter. These objects I accomplish in the manner illustrated in the accompanying drawings, in which—

Figure 1 is a view in perspective of the lower portion of a ladder having my improved 30 supporting-base thereon, and Fig. 2 is an enlarged sectional view taken between the adjoining inner ends of said sections.

Similar numerals refer to similar parts throughout both views.

In carrying out my invention I provide the 35 front surface or face of each of the legs 1 of a ladder, at a point near its lower end, with a bracket, which consists of a plate 2, secured to said ladder-leg or to the metallic binding 40 of the lower portion thereof, said plate having projecting therefrom and at an angle with the direction of the length of the ladder-leg a keeper or eyepiece 3, the inclination of the outer arms of these keepers being inward, as 45 shown. Through these keepers are adapted to slide portions of base-sections 4, the bodies of the latter being in the form of inclined beams, the inner ends of which are adapted, as indicated in Fig. 1 of the drawings, to meet 50 and abut one against the other at the center of the width of the ladder. Each of these base-sections 4 has secured to its under side and

engaging the outer end thereof a metallic plate or strap 5, the inner ends of these straps being, as indicated more clearly in Fig. 2 of 55 the drawings, curled or rounded to form cylindrical hinge-tongues, which are shown at 6 and 7, said hinge-tongues being jointedly united by a hinge-bolt 8. The rear end portion of this hinge-bolt extends through a longitudinal slot 9 of an upwardly-extending bar 10, which is affixed to the central portions of the ladder-rungs.

Between the outer and inner end portions of each of the sections 4 I recess or cut away 65 portions of the upper sides thereof, whereby the thickness of each of said sections is reduced and inner and outer shoulders 11 and 12 are formed. Only these reduced portions of the base-sections are embraced by the keepers 3, the forward shoulders 11 serving by contact with the upper portions of said keepers to limit the outward movement of the sections and the outer shoulders 12 serving to similarly limit the inward and upward movement thereof. As indicated at 13, I provide the outer ends of the sections 4 with oppositely-located downwardly-projecting foot-plates, the lower projecting ends of which are, 70 as indicated in the drawings, toothed or serrated to insure their proper engagement with the ground or other surface upon which the same may bear.

On the outer end of the bolt 8 I hinge or fulcrum a projection 14 of a hand-ring 15, 85 this ring projection being formed with a cam extension, which when the ring is turned upward to the position indicated in the drawings exerts sufficient pressure against the lower portions of the sections 4 to tightly 90 bind said section between the guide 10 and said cam. It is obvious that when the ring 15 is turned downward and the pressure of the cam thus relieved the sections 4 may be forced inward or outward, resulting in the 95 traveling of the bolt 8 upward or downward in the guide 10, and permitting thereby the desired adjustment of the sections 4. In this manner it is obvious that the distances which the end portions of the base-sections project 100 beyond the sides of the ladder may be readily controlled by the operator, thereby not only admitting of the supporting-base being adapted for bearing in spaces of various widths, but

admitting of the same being drawn inward in such positions as to be practically out of the way when the ladder is being carried on a truck or not in use.

- 5 Although the herein-described ladder-base is of simple construction and operation, it will readily be seen that its use will provide a safe and substantial bearing for a ladder or lower section thereof which will not only 10 resist tendency toward slipping outward, but which will also resist any tendency toward a lateral or tipping movement of the ladder in either direction.

In case the bearing-feet of one of the beam-sections should rest upon a more yielding surface than the other it is obvious that the 15 tendency toward that side of the ladder sinking would be greatly overcome by the contact of the under side of the beam-section with 20 the ground after the sinking of the toothed projections of the feet 13. It will thus be seen that not only is the ladder provided with a lateral extended base, which will insure a 25 substantial bearing of a lower ladder-section, but that by its use the mounting of ladders by firemen and others may be conducted with comparative safety, whether the same be supported upon a smooth or uneven surface.

Having now fully described my invention, 30 what I claim, and desire to secure by Letters Patent, is—

1. In a base attachment for ladders, the combination with a ladder-frame, and keepers projecting from the legs thereof of a base attachment formed of two sections and having a sliding support in said keepers, a central guide carried on said ladder-section and means for locking the inner ends of said base-sections at different heights on said guide, substantially as specified. 35

2. In a base attachment for ladders, the combination with a ladder-section and keepers projecting from the legs thereof, of a base consisting of jointedly-connected sections 4, said sections passing through said keepers, a 40 guide on said ladder-section and means for locking said base-sections at different heights on said guide, substantially as specified.

3. In a base attachment for ladders, the combination with a ladder-section, keepers projecting from the legs thereof and a central guide carried on said ladder, of base-sections 4, a bolt hinging the inner ends of said sections and having a sliding engagement with said guide and a handpiece fulcrumed to the 50 outer end of said bolt and having a cam projection, substantially as specified. 55

FREDERIC S. SEAGRAVE.

In presence of—

C. C. SHEPHERD,
EDWARD M. TAYLOR.
